 I. G. Farbenindustrie Aktiengesellschaft,
 Frankfort-on-the-Main, Germany

Application June 9, 1933, Serial No. 675,126
 In Germany June 16, 1932

8 Claims. (Cl. 274—11)

My present invention relates to a phonograph for band-shaped sound carriers bearing several parallel sound tracks.

One of its objects is to provide for an easy and gradual removal and setting of the sound box and the stylus from and on the film. Another object is to simplify the transfer of the sound box when a band bears a plurality of sound grooves or tracks from one sound groove onto another when the performance of a musical piece is finished. Further objects will be seen from the detailed specification following hereafter. Reference is made to the accompanying drawing in which Fig. 1 is a side view of the device according to this invention. Fig. 2 is a plan view of the same device partially in section.

According to this invention the adjustment of the stylus on the sound carrier is facilitated by disposing an eccentric between the stylus and the pivoting axis of the arm carrying the sound box, whereby this arm can be gradually lifted and lowered in the direction vertical to the band-like sound carrier. Furthermore according to this invention a bolt with a coarsely pitched thread is located inside the axle of the box arm thus allowing movement of the arm axially, i. e. transversely to the travelling direction of the sound band.

In order to bring the stylus into engagement with the desired sound groove the lateral movement of the arm carrying the sound box is controlled by a milled disk provided on the threaded bolt. This disk bears marks and notches, numbered in accordance with the sound grooves provided on the sound carrier. By adjusting the disk to the desired mark, the sound arm is laterally moved by spring action so as to engage the desired sound groove.

The invention will now be described in detail with reference to the accompanying drawing.

When the apparatus is in operation the box arm 1 with the sound box 2 bearing the stylus 3 rests on the sound band 4 which at the point where the stylus touches the record is supported by a roller 5. The arm 1 can be lifted and lowered and is moreover movable in a direction transversely to the travel of film.

The lifting and lowering motion of the sound arm 1 is effected by an eccentric 6 which can be rotated by means of the milled knob 7. In order to ensure an exact adjustment the arm 1 is provided with an adjusting pin 8, the position of which is controllable with respect to the arm 1 and which alone comes in contact with the eccentric 6. The opening 9 in the arm 1 is dimen-

sioned such that the eccentric 6 can freely turn inside the arm 1. The axle of the eccentric 10 forms at its end situated behind the base plate 11 of the apparatus a portion 12 flattened on two sides and a spring 13 is pressed against this portion 12 (see Fig. 1). By this means the eccentric is stopped at its highest and lowest position.

As the sound band bears several parallel sound tracks 14, it is necessary that the box arm can also be adjusted transversely to the travelling direction of the film. In the construction according to this invention this is realized by providing, within the axle 15 around which the sound arm 1 is tiltable, a bolt 16 threadedly engaging said axle with a thread of coarse pitch. This bolt 16 bears 15 at its one end an adjusting disk 17, the other end 16a of the threaded bolt being screwed out of or into the axle 15 of the sound arm by turning the adjusting disk. In this manner the sound arm by its contact with the end of the bolt 16a 23 is more or less displaced in direction of the arrow, i. e. transversely to the travelling direction of the sound band. For exactly controlling the transverse movement, there is provided a set screw 19 fixed to the part 18 of the sound arm 1 25 which embraces the bolt 16 in form of a cap. By means of this screw 19 the stylus can be adjusted exactly so that it engages the outermost sound groove 14a.

The adjusting disk 17 has a milled edge and 30 on its side nearest the spectator bears a scale 20 each mark of which corresponds to a sound groove 14. Besides the numbers, disk 17 bears notches 21, which are engaged by a pin 22 located in the housing 23 and pressed against the disk by means 35 of a spring. By this device the scale disk 17 can be adjusted and arrested in any position of the arm 1 in a direction transverse to the direction of travel of the sound carrier. The casing 23 furthermore has an inspection opening 24 through 40 which only that number on the scale 20 is visible which corresponds with the sound groove which the stylus engages. When turning the threaded bolt 16 backward into its zero position by means of the disk 17, the arm 1 will automatically follow the movement of the bolt, as the spring 25 by way of the arm 26 and screw 27 constantly presses the end 16a of the sound arm, embracing the bolt 16a in the way of a cap, against the bolt end 16a (cf. the arrow shown beside the spring 25). In consequence, after turning the scale disk 17 in its zero position, that is when the number 1 is seen in the opening 24 in the present case, the stylus will engage the first sound groove 14a.

The arm 1 may easily be removed, as the arm 26 carrying the screw 27 for pressing the screw head 18 and, therefore, also the cap 18 against the bolt 16 may easily be withdrawn against the action of the spring 25, by the milled knob 28 (cf. Fig. 2) and moved aside.

In order to compensate for inaccuracies in the manufacture and differences in the spacing of the sound grooves 14, which may be due to shrinkage of the film, the sound arm 1 is subdivided along line 1a. That piece of the arm 1 carrying the sound box 2 is connected with the piece 30 hinged to the axle 15 by a pin 28. The pin 28 is fixedly mounted on the part 30, but does not exactly fit in the other part of the box arm, but with some circumferential play, so that the box 2 and the stylus 3 inserted therein can swing by fractions of a millimeter in the direction of travel of the sound band in case the sound groove is somewhat displaced with regard to the position of the stylus controlled by the disk 17.

The device according to this invention may be used for the recording or reproduction of sound.

What I claim is:

1. In a phonograph apparatus, in combination, a sound arm comprising a first and a second part, means for movably connecting said two parts of said sound arm, a sound box connected with the first part of said sound arm, a base plate, an axle fixedly mounted on said base plate, the second part of said sound arm being rotatable about this axle, and means cooperating with said base plate and said second part for displacing said second part in the direction of said axle.

2. In a phonograph apparatus, in combination a sound arm comprising a first part and a second part, a pin fixedly mounted on said second part and connected with said first part so that the latter is slightly rotatable about said pin, a sound box connected with the first part of said sound arm, a base plate, an axle fixedly mounted on said base plate and provided with a boring, said second part embracing said axle in form of a cap, a bolt screw threaded in said boring provided with a knob and means for pressing said second part against said bolt.

3. In a phonograph apparatus, in combination a sound arm comprising a first part and a second part, a pin fixedly mounted on said second part and connected with said first part so that the latter is slightly rotatable about said pin, a sound box connected with the first part of said sound arm, a base plate, an axle fixedly mounted on said base plate and provided with a boring, said second part embracing said axle in form of a cap, a bolt screw threaded in said boring provided with a knob, a screw fixed to said cap so that it bears against said bolt, thus allowing to vary the distance of said second part from said bolt, a hollow shaft mounted on said base plate, a shaft and a spring mounted in said hollow shaft, said spring pressing said shaft in the direction of said base plate, a lever mounted on said shaft perpendicularly to the same a screw fixed to said lever, said lever being rotatable with said shaft in said hollow shaft so that the screw fixed on it can be brought in engagement with said screw on said cap, thus pressing by the action of said spring said second part against said bolt.

4. In a phonograph apparatus, in combination a sound arm comprising a first part and a second part, a pin fixedly mounted on said second part and connected with said first part so that the

latter is slightly rotatable about said pin, a sound box connected with the first part, an opening provided in said first part and means engaging said first part for gradually lifting and lowering said sound box, a base plate, an axle fixedly mounted on said base plate and provided with a boring, said second part embracing said axle in form of a cap, a bolt screw threaded in said boring provided with a knob, a screw fixed to said cap so that it bears against said bolt, thus allowing to vary the distance of said second part from said bolt, a hollow shaft mounted on said base plate, a shaft and a spring mounted in said hollow shaft, said spring pressing said shaft in the direction of said base plate, a lever mounted on said shaft perpendicularly to the same a screw fixed to said lever, said lever being rotatable with said shaft in said hollow shaft so that the screw fixed on it can be brought in engagement with said screw on said cap, thus pressing by the action of said spring said second part against said bolt.

5. In a phonograph apparatus, in combination, a sound arm comprising a first part and a second part, a pin fixedly mounted on said second part and connected with said first part so that the latter is slightly rotatable about said pin, a sound box connected with the first part, an opening provided in said first part a base plate, a shaft rotatably mounted on said base plate, an eccentric fixed on said shaft and engaging in said opening so that on rotation of said eccentric said sound arm is lifted or lowered, an axle fixedly mounted on said base plate and provided with a boring, said second part embracing said axle in form of a cap, a bolt screw threaded in said boring provided with a knob, a screw fixed to said cap so that it bears against said bolt, thus allowing to vary the distance of said second part from said bolt, a hollow shaft mounted on said base plate, a shaft and a spring mounted in said hollow shaft, said spring pressing said shaft in the direction of said base plate, a lever mounted on said shaft perpendicularly to the same a screw fixed to said lever, said lever being rotatable with said shaft in said hollow shaft so that the screw fixed on it can be brought in engagement with said screw on said cap, thus pressing by the action of said spring said second part against said bolt.

6. In a phonograph apparatus, in combination a sound arm comprising a first part and a second part, a pin fixedly mounted on said second part and connected with said first part so that the latter is slightly rotatable about said pin, a sound box connected with the first part, an opening provided in said first part, a base plate, a shaft rotatably mounted on said base plate, an eccentric fixed on said shaft and engaging said opening so that on rotation of said eccentric said sound arm is lifted or lowered, means for fixing said eccentric in its highest and lowest position, an axle fixedly mounted on said base plate and provided with a boring, said second part embracing said axle in form of a cap, a bolt screw threaded in said boring provided with a knob, a screw fixed to said cap so that it bears against said bolt, thus allowing to vary the distance of said second part from said bolt, a hollow shaft mounted on said base plate, a shaft and a spring mounted in said hollow shaft, said spring pressing said shaft in the direction of said base plate a lever mounted on said shaft perpendicularly to the same a screw fixed to said lever, said lever being rotatable with said shaft in said hollow

shaft so that the screw fixed on it can be brought in engagement with said screw on said cap, thus pressing by the action of said spring said second part against said bolt.

5 7. In a phonograph apparatus, in combination a sound arm comprising a first part and a second part, a pin fixedly mounted on said second part and connected with said first part so that the latter is slightly rotatable about said pin, a sound 10 box connected with the first part, an opening provided in said first part, a base plate, a shaft rotatably mounted on said base plate and having two flattened portions opposite to each other, an eccentric fixed on said shaft and engaging said opening so that on rotation of said eccentric said sound arm is lifted or lowered, a spring mounted on said base plate and bearing against said shaft at the position of said flattened portions so that said eccentric is stopped in its upper and lower 15 position, an axle fixedly mounted on said base plate and provided with a boring, said second part embracing said axle in form of a cap, a bolt screw threaded in said boring provided with a knob, a screw fixed to said cap so that it bears against said bolt, thus allowing to vary the distance of said second part from said bolt, a hollow shaft mounted on said base plate, a shaft and a spring mounted in said hollow shaft, said spring

pressing said shaft in the direction of said base plate, a lever mounted on said shaft perpendicularly to the same a screw fixed to said lever, said lever being rotatable with said shaft in said hollow shaft so that the screw fixed on it can be brought in engagement with said screw on said cap, thus pressing by the action of said spring said second part against said bolt.

5 8. In a phonograph apparatus, in combination a sound arm comprising a first part and a second part, a pin fixedly mounted on said second part and connected with said first part so that the latter is slightly rotatable about said pin, a sound box connected with the first part, an opening provided in said first part, a base plate, a shaft rotatably mounted on said base plate and having two flattened portions opposite to each other, an eccentric fixed on said shaft and engaging said opening so that on rotation of said eccentric said sound arm is lifted or lowered, a 10 spring mounted on said base plate and bearing against said shaft at the position of said flattened portions so that said eccentric is stopped in its upper and lower position a pin adjustably mounted in said first part and bearing against 15 said eccentric, so that the distance of said first part from said eccentric can be varied.

LEO GOLDHAMMER.
